UNITED STATES PATENT OFFICE.

JOSEPH E. MEYER, OF WOODSIDE, NEW YORK, ASSIGNOR TO R. HOE & CO., INC., OF NEW YORK, N. Y., A CORPORATION OF NEW YORK.

WEB-FEEDING MECHANISM.

Application filed August 3, 1925. Serial No. 47,731.

This invention relates to certain improvements in web feeding mechanisms.

In certain types of web feeding mechanisms, particularly mechanisms for forwarding and directing webs such as are used in web printing machines, it is frequently desirable to change the run of the web from one direction to a direction at an angle thereto, usually a right angle. This is done by means of rolls or bars commonly known as turner bars, these bars being set at the desired angle to effect the change in direction required, the web being drawn against these bars and turning thereover.

With this class of mechanism it frequently happens that if the bars over which the web is led are not dry or if a fresh printed portion of the web comes in contact with the bar, smutting of the web occurs, thereby producing imperfect products. Another feature of this type of mechanism is that an unnecessary amount of friction develops between the web and the roll, so that the web does not run through the mechanism with the desired facility.

It is an object of the present invention to provide a construction by the use of which the web is so supported between its margins or other unprinted portions that the printed portions of the web do not come in contact with the surface of the bar as the web turns around the bar.

A further object of the invention is to provide a construction by which this may be accomplished in a simple and inexpensive manner and in which the friction between the web and the roll or bar is substantially reduced.

With these and other objects not specifically referred to in view, the invention consists in certain novel parts, arrangements and combinations which will be described with reference to the accompanying drawings and the novel features pointed out in the claims hereunto annexed.

In the drawings—

Figure 1 is a plan view of so much of a web feeding mechanism as is necessary for an understanding of the invention, the view being partly broken away;

Figure 2 is a side view looking in the direction of arrow 2 of Fig. 1;

Figure 3 is a detail of one end of an improved roll; and

Figure 4 is a sectional view of one of the

improved bars or rolls, taken on the line A—A of Fig. 1, looking in the direction of arrow 4 of that figure.

Referring now to these drawings, the various parts of the machine are supported in suitable frames indicated at *a*, *b* and *c*, of any usual or desired construction. In accordance with the invention, means are provided for preventing the printed surface of the web from coming in contact with the direction changing devices by which the web direction is changed, the printed portion of the web being kept out of contact with the surface of such devices. While this may be accomplished in various ways, in the particular construction illustrated, this is effected by providing a thin layer of air or the like around the turner on which the unprinted portion of the web, in effect, floats and is kept away from the turner surface.

While the particular mechanism by which this may be effected may vary widely in character, in the particular construction shown the devices for changing the direction of the web are in the form of rolls or bars indicated by the numeral 1, a sufficient number of these bars being provided for the purposes required in any particular press. These bars or rolls are or may be identical in construction and a description of one will suffice for all.

As shown, this bar is a hollow bar and is provided with a series of apertures which are shown in the form of long slots 2. This construction effects a good distribution of air over the roll surface, but it is understood that other forms of apertures, such as perforations, can be used within the invention.

These bars are, in the particular construction shown, arranged at an angle of 45° to the run of the web and are provided at each end with solid heads 3, 4, which are supported in brackets 5, 6, and held in position in the brackets in any suitable manner, as by bolts 7. In the best constructions, these bars are adjustable so that the angle of the bar may be varied as desired. In the particular construction illustrated the brackets 5, 6 are secured to short shafts 8, 9, these shafts being slidingly mounted in brackets 10, 11. One of these shafts, as shaft 9, has threaded thereto a handwheel 12 held in position in any suitable manner, as by a washer 13.

2

In the best constructions means are provided for adjusting the bar in the brackets 5, 6 and to effect this there is provided at each end of the roll or bar adjusting screws 15 passing through a slotted extension 14 of the brackets 5, 6, before referred to. The bolts 7 are tapped into the heads 3, 4 from the under side, passing through a hole in the brackets 5, 6 larger than the 10 screws, as shown at the right hand side of Fig. 2. By loosening the bolts 7, therefore, and turning the screws 15, the bars 1 may be given a slight adjusting movement to vary the angle of the bar and thus compensate for irregularities in the web. By 15 adjusting the hand-wheel 12, the whole bar, brackets and heads may be given a back and forth movement to adjust the web with respect to the margin bearers 22.

20 Air, or other suitable fluid to form the supporting layer of the web, is supplied to the roll under pressure, in any suitable manner. In the particular construction illustrated, one of the heads, as the head 3 of the bar, has a hole or passageway 16 formed therein, this hole connecting to the inside of the bar. This aperture is connected at its outer end with a flexible fitting 17, which, through elbow coupling 18, is connected to an air supply pipe 19, to which air is supplied under pressure from any suitable source, not shown. The web marked W 25 is forwarded to the turner bars over the roll 20 and under the usual propeller roll 20 21.

If desired, the margins or unprinted portions of the web may be supported on 30 bearers, these bearers being shown in the form of strips 22 shown as provided at the two side margins of a web. It will be understood that while these bearers are desirable under certain circumstances, they may be 40 omitted if desired.

It will be seen that, with the construction 45 shown and described, a very effective anti-smut device has been provided in that the printed surface of the web does not come in contact with the surface of the turner rolls or bars. Furthermore, friction has been largely eliminated and an easy run of 50 the web is effected.

While the invention has been shown and described in its preferred form, it will be understood that various changes and variations 55 may be made in the particular form of turner devices used and the particular means for mounting these devices in the machine, without departing from the invention as defined in the appended claims.

60 What is claimed is:

1. In a web feeding mechanism, the combination of a hollow roll or bar over which a web is led, perforations in the bar widthwise thereof and means for supplying air under pressure through the perforations, 65 margin bearers on the bar, brackets in which the bar is mounted, mechanism for moving the brackets for adjusting the bearers relatively to the web, and adjusting mechanism for adjusting the angle of the bar relatively 70 to the web.

2. In a web feeding mechanism, the combination of a hollow roll or bar over which a web is led, apertures in the bar and means for supplying air under pressure through the 75 apertures, margin bearers on the bar, brackets for the bar, adjusting mechanism to which the brackets are secured for moving the bar for bearer adjustment, bolts extending through a clearance in the brackets for 80 securing the bar thereto and an adjusting screw for effecting an angular movement of the bar relatively to the bracket.

In testimony whereof, I have hereunto set my hand.

JOSEPH E. MEYER.
